(57) **CLAIM**

The ornamental design for a chef jacket, as shown and described.

DESCRIPTION

FIG. 1 is a front perspective view of a chef jacket showing my new design;

FIG. 2 is a front elevation view thereof;

FIG. 3 is a rear elevation view thereof;

FIG. 4 is a front elevation view showing separation of an apron portion;

FIG. 5 is a front elevation view showing the jacket front in a partially open position;

FIG. 6 is a right side elevation view thereof;

FIG. 7 is a left side elevation view thereof;

FIG. 8 is a top plan view thereof; and,

FIG. 9 is a bottom plan view thereof.

The dotted lines shown in the drawings illustrate portions of the chef jacket that form no part of the claimed design.

The dashed lines shown in the drawings illustrate boundaries that form no part of the claimed design.
